(57) **CLAIM**

The ornamental design for a golfing GPS display as shown and described.

DESCRIPTION

FIG. 1 is a bottom front perspective view of a golfing GPS display according to the present invention;

FIG. 2 is a front view of the GPS display according to the present invention;

FIG. 3 is a back view of the GPS display according to the present invention;

FIG. 4 is a left side view of the GPS display according to the present invention;

FIG. 5 is a right side view of the GPS display according to the present invention;

FIG. 6 is a top view of the GPS display according to the present invention;

FIG. 7 is a bottom view of the GPS display according to the present invention;

FIG. 8 is a detailed bottom front perspective view of the GPS display according to the present invention; and,

FIG. 9 is a detailed bottom front perspective view of the GPS display according to the present invention.

The broken line showing of the golfing GPS display is for the purpose of illustrating portions of the GPS display which form no part of the claimed design.

1 Claim, 8 Drawing Sheets
